GARBAGE HOLDER

Travis O. Smith, Kansas City, Mo., assignor, by
mesne assignments, to David M. Lorenz, John-
son County, Kans.

Application August 2, 1943, Serial No. 497,095

6 Claims.

(Cl. 312—163)

This invention relates to household equipment and particularly to garbage holders of the type employing containers or receptacles disposable with the garbage.

The handling of garbage or refuse from the kitchen is always a disagreeable task. Pails commonly used for this purpose quickly become contaminated and must be frequently cleaned. Often they are filled to overflowing before the garbage collector makes his round and not infrequently, the pails are turned over by dogs and the garbage is spilled therefrom.

This invention has for its primary object the provision of a garbage holder adapted to be positioned in a kitchen or other convenient location, and constructed to support a disposable container in normally closed condition but embodying mechanism whereby the container may be quickly and conveniently opened for the reception of refuse or garbage.

Another object of the invention is to provide a garbage holder having a separable table top, with one section thereof arranged to be moved coincidentally with the opening of the receptacle in order to expose the mouth of the latter when garbage is to be deposited therein.

It is a further object of the invention to provide a garbage holder having a frame which may be readily collapsed for storage or shipment.

A yet further aim of this invention is to provide a garbage holder of simple, light weight construction, which can be manufactured at low cost and easily assembled for use.

These and other objects of the invention have been accomplished with structure illustrated in the accompanying drawing, wherein:

Fig. 1 is a perspective view of a garbage holder constructed in accordance with this invention.

Fig. 2 is a fragmentary section of the upper end of the holder taken on line II—II of Fig. 1; and

Fig. 3 is a fragmentary section on an enlarged scale, of the upper end of a garbage receptacle in closed condition and anchored to cross members of the frame.

In constructing the garbage holder, a pair of spaced apart parallel legs 6, of flat steel bars or the like, are pivotally connected in crossed relation with a similarly spaced pair of legs 8 to produce a collapsible frame. A rod 10 having its opposite ends extended through the crossed legs of pairs 6 and 8 is provided with nuts 12 on either side of the legs to maintain the same in properly spaced and assembled condition. Identical rods 14 and 16, provided respectively

with nuts 18 and 20, are likewise employed to hold the lower ends of pairs 6 and 8 in fixed spaced relation. The extreme lower ends of the legs may be twisted and bent to form feet 22.

5 A spacer rod 24, extended through the upper ends of legs 6, also pivotally mounts one end of each of a pair of connecting bars 26 adjacent said legs, nuts 28 being employed to hold the bars in assembled condition with legs 6. The opposite ends of bars 26 are notched as shown at 30 for engaging the respective ends of a spacer rod 32 extended through the upper ends of legs 8. It will be noted that pairs of nuts 34 threaded on each end of rod 32 serve to clamp the adjacent ends of bars 26 and legs 8 together.

10 A fixed cross member 36 having laterally bent ears 38 is secured to bars 26 at a point intermediate their ends by bolts 40 extended through the ears and connecting bars. In cooperation with the fixed cross member is a movable cross member 42, preferably constructed of angle-iron, with its vertical leg 44 sufficiently short to extend between connecting bars 26 but with a horizontal leg 46 of enough length to project at each end through elongated slots 48 formed in bars 26.

15 Seated on the upper edge of cross member 36 is a channel 50 having its lower inside edge provided with a series of rebent upwardly directed hooks 52. Similarly, a channel 54 is seated on movable member 42 and provided on its inside lower edge with hooks 56. These hooks 52 and 56 are adapted to engage the reinforced upper edges 58 and 60 of a disposable garbage bag or receptacle 62. It is contemplated that receptacles 62 be made of waterproofed paper or other suitable flexible material.

20 As will be observed from Figs. 2 and 3, the edges 58 and 60 forming the mouth of the receptacle, are normally contiguous, being held in such condition by springs 64 having their opposite ends respectively attached to rod 24 and to the projecting ends of leg 46 of movable cross member 42.

25 In order to provide for convenient opening of the mouth of receptacle 62, a pair of rollers 66 having grooves 68 are mounted on rod 32 and retained in fixed, spaced condition by sleeves 69 on the rod. Lines 70, running in the grooves 68 of rollers 66, each have one end attached to horizontal leg 46 of member 42 and the opposite end secured to the bight 72 of a U-shaped treadle 74. Arms 76 of the treadle have their outer ends pivotally connected to legs 6 adjacent the lower end of the latter by bolts 78.

30 In order to further extend the utility of the

holder, a separable table top, comprising a relatively stationary section 80 and a movable section 82, may be provided to cover the upper end of the device. The meeting line of the separable sections is preferably immediately above the closed mouth of receptacle 62. Stationary section 80 having a peripheral depending flange 84, extends beyond the front and side edges of the holder frame and may be hingedly mounted on rod 24 by a tubular link 86 having an angular leg 88 fixed to the lower face of section 80. The rear portion of flange 84 rests on the upper edges of bars 26, as clearly shown in Fig. 2. When it becomes necessary to remove or replace receptacle 62, section 80 may be swung on rod 24 to the position shown in dotted lines in said figure, where it will in no way interfere with manipulation of the receptacle.

Movable section 82 is also provided with a peripheral depending flange 90. A channel 92 has one leg fixed to the lower face of section 82 near its front edge and its other leg secured by bolts 94 to cross member 46. The rear portion of section 82 preferably rides on rollers 66. As cross member 46 is moved in a direction away from member 38, section 82 is carried along as indicated in dotted lines in Fig. 2. The direction of rotation of rollers 66 is such as to assist in this movement. Accordingly, when the mouth of the receptacle is opened, the sections of the table top will be separated to uncover the mouth. Simultaneously with the closing of the receptacle, the movable section 82 will return to its original position.

The operation of the device will be obvious from the foregoing disclosure. A relatively light pressure on treadle 74, simultaneously moves table section 82 in a direction away from section 80 and opens the mouth of receptacle 62. After the garbage has been discharged therein, pressure is removed from the treadle and springs 64 return cross member 42 and top section 82 to their original positions, and simultaneously therewith, close the mouth of the container.

When the receptacle has been filled, it is removed from hooks 52 and 56 and disposed together with the garbage in any convenient manner. A clean container is then mounted on the hooks and the device is ready for further use.

Only one form of the invention has been shown and described, and since it is conceivable that various modifications thereof might be made without departing from the spirit of this invention, it is desired to be limited only by the scope of the appended claims.

Having thus described the invention, what I claim as new and desire to secure by Letters Patent is:

1. A garbage holder comprising a frame having a fixed and a movable member; a flexible container having opposite sides of its mouth respectively attached to said fixed and movable members; a pulley on the frame; a treadle pivotally mounted on the frame; a line running over the pulley and having its opposite ends respectively connected to the movable member and to said treadle for opening the mouth of the container when said treadle is depressed; and a spring for retracting the movable member to close the mouth of the container.

2. A garbage holder comprising pairs of legs;

bars connecting the upper ends of said pairs of legs each bar having a slot; a fixed cross member secured to said bars; a movable member having its ends projected through and movable along said slots; a flexible container having opposite sides of its mouth respectively attached to said fixed and movable members; means for drawing the movable member away from the fixed member to open the mouth of the container; and means for retracting said movable member to close the mouth of said container.

3. A garbage holder comprising pairs of legs; bars connecting the upper ends of said pair of legs, each bar having a slot; a fixed cross member secured to said bars; a movable member having its ends projected through and movable along said slots; a flexible container having opposite sides of its mouth respectively attached to said fixed and movable cross members; a treadle pivotally mounted on said legs; flexible means connecting the treadle with the movable cross member for opening the mouth of the container; and resilient means for returning the cross member and treadle to their original positions for closing the mouth of the container.

4. A garbage holder comprising a frame having a fixed and a movable member; a table top section secured to the movable member; a flexible container having opposite sides of its mouth, respectively, attached to said fixed and movable members; means for moving the last-named member together with said top section away from the fixed member to open said mouth; and means for returning said movable member to close the mouth of the container.

5. A garbage holder comprising a frame having a fixed and a movable member; a separable table top for the frame comprising a stationary and a movable section, said stationary section being mounted on said fixed member of the frame; means for securing the movable section to said movable member; a flexible container having opposite sides of its mouth respectively attached to said fixed and movable members; means for moving the last-named member together with said movable section away from the fixed member and stationary section to open said mouth; and means for returning the movable member and movable section to close the mouth of the container and bring said top sections into contiguous relation to each other, the meeting line of said top sections being in substantial alignment with the closed mouth of the container.

6. A garbage holder comprising a frame having a fixed and a movable cross member; a flexible container having opposite sides of its mouth respectively attached to said fixed and movable members; a pulley on the frame; a treadle pivotally mounted on the frame; a line running over said pulley and having its opposite ends respectively secured to the movable cross member and to said treadle for opening the mouth of the container when said treadle is depressed; means for retracting the movable member to close the mouth of the container; and a table top having its forward edge secured to and supported by the movable cross member and having its rear portion carried by said pulley.
